(57) **CLAIM**

The ornamental design for a smart watch band with protective case, as shown and described.

DESCRIPTION

FIG. 1 is a front, right, and top perspective view of a smart watch band with protective case showing my new design; FIG. 2 is a rear, left, and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof;

FIG. 9 is an enlarged view of portion 9 shown in FIG. 1; FIG. 10 is another perspective view of the smart watch band with protective case of FIG. 1, shown with additional environmental structure; and,

FIG. 11 is another perspective view of the smart watch band with protective case of FIG. 10, shown in an alternate configuration.

The dash-dash broken lines in the drawings depict portions of the smart watch band with protective case or environmental subject matter that form no part of the claimed design. The dot-dash broken lines in the drawings represent boundaries of the enlarged portion that form no part of the claimed design.
